UNITED STATES PATENT OFFICE.

KARL NEUMANN, OF MILWAUKEE, WISCONSIN.

ARTIFICIAL LIMB.

Application filed October 27, 1926. Serial No. 144,440.

This invention relates to artificial limbs. In artificial limbs heretofore designed the thigh and shank portions are ordinarily pivotally connected to swing about a definite axis which bears a fixed relation to both portions in all angular positions thereof. In fact the knee joint ordinarily includes a pivot pin fixed to intersect the longitudinal axis of both portions. Such a disposition of the pivot is 10 objectionable in that the leg tends to buckle under the weight of the wearer when standing in erect position. Attempts to overcome this objection by arranging the pivot in the rear of the axes of these portions have not 15 proven satisfactory because this results in an extremely unnatural knee action. A rearwardly positioned pivot causes an unnatural bulging of the front portion of the knee and an unnatural elevation of the adjacent portion of the thigh when the limb is bent as in a sitting posture.

One object of the present invention is the provision of a knee joint which will closely simulate the action of a natural knee and at 25 the same time sustain the weight of the wearer without danger of buckling. This I accomplish by the use of lever mechanism which when the limb is straight will react under load to resist buckling. 30 Another object is the provision of an improved ankle joint which will function to provide a natural foot action about a definite axis and at the same time permit a slight deviation from this true action to permit the foot to 35 accommodate itself to slight unevenness in the tread surface.

Another object is the provision of improved means for coordinating the knee and ankle actions.

40 Other objects and advantages will appear from the following description of an illustrative embodiment of the present invention.

In the drawings:

Figure 1 is a longitudinal sectional view of 45 an artificial limb constructed in accordance with the present invention.

Fig. 2 is a transverse sectional view of the knee joint taken substantially along the line 2-2 of Figure 1.

50 Fig. 3 is a transverse sectional view of the shank portion taken substantially along the line 3-3.

Fig. 4 is a vertical sectional view of the 55 ankle joint taken substantially along the line 4-4.

The artificial limb selected for illustration

includes the usual thigh portion 10, shank portion 11, and foot 12 each constructed and fitted to the other in a manner well known in the art. The operating connections between these parts are new, however, and will be described in detail.

The thigh portion is supported upon the upper end of a lever 13, mounted intermediate its ends upon a transverse pivot pin 14, 65 fixed within the shank portion 11 intermediate the ends thereof. In the limb shown the pivot pin 14 extends through two inwardly projecting lugs 15 within the shank portion which support the pin and serve to retain the 70 lever 13 within a central plane of the shank portion. The upper end of the lever 13 carries two pins 16 and 17 projecting laterally therethrough and through curved slots 18 and 19, respectively, formed in an appropriate bracket 20 fixed to and depending from the thigh portion 10.

The bracket 20 shown is of inverted U form. It includes a top plate 21, rigidly secured to a transverse partition 22 formed in the lower portion of the thigh 10, and two integral side plates 23 depending therefrom. The lower ends of the side plates 23 are preferably rigidly connected by means of a rod 24 or the like which cooperates with the top 85 plate 21 to maintain a definite uniform spacing between the plates. Each end of pin 16 rides in the slot 18 formed in each side plate and each end of pin 17 rides in the slot 19 formed in each side plate. Appropriate 90 spacer sleeves 25 are preferably fitted on each pin in order to properly position the lever. The side plates are also slotted, as at 26, to receive a transverse guide pin 27, fixed within the upper end of the shank portion, and serving to position and guide the bracket within the shank portion.

It will be noted that the slots 18 and 19 are so disposed that with the limb in the straight full-line position, the lever 13 is inclined 100 rearwardly from its supporting pivot pin 14. It will also be noted that the slots are so directed that, in order for the thigh portion to swing downwardly from this upright position toward the dotted line position, the upper end of the lever must swing forwardly 105 toward the dotted line position. With the limb straight and the lever inclined rearwardly however a vertical load applied to the thigh portion reacts against the lever to prevent forward swinging thereof, and the limb is thus locked against buckling under this 110

vertical load. In this respect the lever 13 and bracket 20 function as an ordinary toggle mechanism which when adjusted beyond dead center position in one direction will resist 5 buckling in the opposite direction. A knee joint constructed in this manner will permit the wearer to rest his entire weight upon the straight limb, while standing, without fear of the same buckling beneath him.

10 The usual slip straps 28 and 29 are preferably employed to control the knee action when walking. These are associated with the well known shoulder harness in the customary manner. The forward strap 28 is passed 15 over the pin 17 and fixed to the pin 16, so that when tensioned it tends to pull pin 16 upwardly in the slot 18 to thereby bend the knee. The rear strap 29 passes over the pin 27 and beneath the pin 24, and is fixed to the 20 pin 16, so that tension applied thereto draws the pin 16 toward the lower end of slot 18 to thereby straighten the knee. Thus as the limb is advanced to take a forward step the tension thereby produced in strap 29 holds 25 the knee against bending so that the limb remains in a straight position ready to assume the weight of the wearer. Then as the limb is swung rearwardly the tension produced in strap 28 causes the knee to bend slightly, 30 thereby swinging the shank portion upwardly and lifting the foot clear of the tread surface. This alternate tensioning of the straps is a condition well known in the art and therefore requires no further explanation.

35 In the limb shown the foot 12 is connected to the shank portion 11 through a pivot pin 30 anchored at its opposite ends in appropriate spaced brackets 31 secured to the shank portion. This pin 30 is snugly fitted within 40 an eye 32 of an anchor bolt 33 fixed in the central portion of the foot. The brackets 31 bear upon appropriate resilient pads 34, preferably of rubber, embedded in the sides of the foot. This connection permits the foot to 45 swing freely about the axis of the pin 30. The pads 34 sustain the load imposed upon the limb and also yieldably permit slight lateral flexibility to permit the foot to accommodate itself to unevenness in the tread 50 surface.

Provision is preferably made for coordinating the knee and ankle actions. In the limb shown this is accomplished by extending the lever 13 downwardly and effecting an operative engagement between it and the foot. In this instance an upright yoke 35, anchored to the foot, is forked as at 36 to receive a transverse loop portion 37 formed at the lower end of the lever. The arrangement is 55 such that all movements of the lever 13, resulting from a bending of the knee, are transmitted through the yoke 35 to bend the ankle.

60 Various changes may be made in the embodiment of the invention hereinabove de-

scribed without departing from the invention as defined in the appended claims.

I claim:

1. In an artificial limb the combination of thigh and shank portions, a lever rockably 70 mounted in one of said portions, a bracket carried by the other of said portions and having a load sustaining connection with said lever, and a guide connection between said bracket and said first named portion. 75

2. In an artificial limb the combination of a shank portion, a lever rockably supported thereby, a thigh portion rockably engaged with and supported by said lever, and means forming a guide connection between said portions 80 independently of said lever.

3. In an artificial limb the combination of a shank portion, an upright lever rockably supported thereby, a thigh portion, a bracket depending from said thigh portion into said 85 shank portion and rockably engaged with and supported by said lever, and means forming a guide connection between said portions independently of said lever.

4. In an artificial limb the combination of 90 a thigh portion, a bracket depending therefrom, slots in said bracket, a shank portion, an upright lever rockably supported by said shank portion, and means on said lever slidably engaged in said slots to form a load sus- 95 taining connection therebetween.

5. In an artificial limb the combination of a thigh portion, a shank portion, a bracket depending from said thigh portion into said shank portion, a slot in said bracket, a guide 100 pin fixed in said shank and engaged in said slot, an upright lever rockably mounted within said shank portion, additional slots in said bracket, and pins carried by said lever and slidably engaged in said slots. 105

6. In an artificial limb the combination of a thigh portion, a shank portion, a bracket depending from said thigh portion into said shank portion, an upright lever rockably supported in said shank portion, two slots of different curvature formed in said bracket, and two pins on said lever spaced longitudinally thereof and engaged within said slots. 110

7. In an artificial limb the combination of a thigh portion, a shank portion, a bracket 115 depending from said thigh portion into said shank portion, a lever rockably supported in said shank portion, and a two point sliding connection between said lever and bracket.

8. In an artificial limb the combination of 120 a thigh portion, a shank portion, a lever rockable in said shank portion, and sliding load sustaining connections between said lever and thigh portion operable to swing said lever during angular adjustment between said 125 thigh and shank portions.

9. In an artificial limb the combination of a thigh portion, a shank portion, a rockable connection between said portions including a 130 thigh supporting lever rockably supported

by said shank portion and movable with respect to both portions during rocking action therebetween, and means forming a guide connection between said portions independently of said lever.

10. In an artificial limb the combination of thigh and shank portions, rockable connections therebetween including a thigh support-

ing lever rockably supported in said shank portion and movable with respect to both portions during rocking action therebetween, and a foot portion rockably connected with said shank portion and actuated by said lever.

In witness whereof, I hereunto subscribe my name this 21st day of October, 1926.

KARL NEUMANN.
